Maurice E. Sparrow
ATTORNEY

UNITED STATES PATENT OFFICE

JOSEPH HILLMAN, OF NEW YORK, N. Y.

SOFT COLLAR

Application filed December 17, 1929. Serial No. 414,786.

This invention relates to improvements in apparel collars and more particularly to collars of the soft turnover type attachably or detachably applied to a shirt.

5 The general object of the invention resides in the provision of means in a practical, economical and convenient form to maintain the front or wing portions of the folded over element of a soft collar firm, unwrinkled and 10 uncurled.

A further object resides in the provision of vertical pockets extending adjacent to the front portions of the folded over element of the collar, adapted to receive stiffening members, the said pockets being formed between 15 a line of stitching marginally uniting the edges of all the plies of the folded over element and another line of stitching uniting the plies other than the top ply thereof, in 20 such manner that the outer or front ply is superposed on and independent of the pockets.

A further object resides in the provision of a folded over collar comprising an outer element and other elements, in which a pocket is formed between any adjacent two of the 25 said other elements by a line of stitching uniting all the elements adjacent their edges and another line of stitching spaced from the 30 former line of stitching uniting together the said two adjacent elements.

These and other objects are attained by the 35 novel construction hereinafter described and shown in the accompanying drawing constituting a material part of this disclosure and in which:

Figure 1 is a front view of a collar, applied 40 to a shirt showing one end of the front edge portions raised, and constructed in accordance with my invention.

Figure 2 is a sectional view in perspective, taken along the line 2—2 of Figure 1 showing a preferred form of my invention.

Figure 3 is a cross section at one end of 45 the front edge portion of the folded over top of the collar, before the plies are turned inside out, embodying the preferred form of my invention.

Figure 4 is a sectional view thereof after 50 the plies are turned inside out.

Figure 5 is a cross section view similar to Figure 3 embodying a modification of my invention.

Figure 6 is a cross section view similar to 55 Figure 4 embodying such modification.

Figure 7 is a cross section view similar to Figure 5 embodying a further modification of my invention.

Figure 8 is a cross section view similar to 60 Figure 6 embodying such further modification.

Referring to the drawing, 10 represents the band provided with the conventional button-hole 11, and 12 represents the folded over top of the collar joined to the band 10 in a 65 conventional manner.

Figure 1 shows the band sewn on a shirt in the customary manner.

The folded over top 12 of the collar is preferably formed of three plies of soft fabric 70 comprising an inner ply 14, an outer ply 15 and an intermediary or interlining ply 16 which are, in the making of the folded over top, superposed one upon the other with the outer ply and intermediary ply outermost 75 and united together by a marginal line of stitching 17. In the customary making of the collar the plies are turned inside out between the outer and inner plies 15 and 14, by which the line of stitching 17 is concealed and the 80 front and bottom of the plies are closely held together at a spaced distance from the edge of the plies by a line of stitching 19.

My invention is a departure from the customary method of making the collar in this 85 respect, that, prior to inserting and stitching the folded over top in and to the band, the inner and interlining plies are united together near their ends by lines of stitching 18, preferably parallel to the lines of stitching 17, and spaced therefrom in such manner that pockets 20 are formed which are adapted to receive stiffening members 21, for the purpose of maintaining the front edges of the folded over top in a firm, unwrinkled and 95 uncurled condition. The lines of stitching 18 may be run prior to the plies being turned inside out or thereafter.

After the plies forming the folded over top 12 have been turned inside out and the line 100

of stitching 18 and 19 run, the said top is attached to the band 10 in the conventional manner.

By constructing the collar in accordance with my invention, I have provided pockets in the front edges of a collar for the purpose of retaining stiffening members which pockets are made free from and independent of the outer layer or ply 15, the chief advantage being that when the stiffening members are inserted in the pockets the outer ply of the collar will not pucker or become distorted in any way.

The pockets 20 are provided with button-holed slits 22 in the inner plies 14 in the folded over top 12 to produce reinforced openings therefor.

Figures 5 and 6 show my invention in a modified form, the former indicating the same prior to the plies being turned inside out and the latter thereafter, in which the pocket 20 is formed by providing an additional strip of material 23, superposing the same on the inner ply 14 at an end thereof, joining its inner end 25 to the inner ply 14 by the line of stitching 26 and uniting its outer end 24 with the plies by means of the marginal line of stitching 17.

Figures 7 and 8 show my invention in a further modified form wherein the pocket 20 is formed by interposing the extra strip of material 23, between the outer and interlining plies 15, 16, respectively, and joining the inner end 25 thereof to the interlining ply 16 by the line of stitching 26, the outer end 24 thereof being united to the plies as hereinabove stated.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:—

1. A collar having a band and a folded over top including an outer ply, an inner ply and an interlining ply, a line of stitching uniting the said plies together adjacent their edges, and another line of stitching spaced from the former line of stitching uniting the inner and interlining plies only, whereby a pocket is formed between the inner and interlining plies.

2. A collar having a band and a folded over top including an outer ply, an inner ply and an interlining ply, a line of stitching uniting the said plies together adjacent their edges, another line of stitching spaced from the former line of stitching uniting the inner and interlining plies only, whereby a pocket is formed between the inner and interlining

plies, and a stiffening member to fit within said pocket.

3. A collar having a band, and a folded over top including an outer element and other elements, a line of stitching uniting the said elements adjacent their edges, another line of stitching spaced from the former line of stitching and uniting together only any adjacent two of the said other elements, whereby a pocket is formed therebetween, said pocket being adapted to receive a stiffening member.

Signed at New York, in the county and State of New York, this 25th day of Oct., 1929.
